Patented Mar. 28, 1922.

Inventor,

Sidney G. Barnstead

By

A. Bligham
Attorney.

UNITED STATES PATENT OFFICE.

SIDNEY G. BARNSTEAD, OF CAMBRIDGE, MASSACHUSETTS.

CONDENSER.

1,411,150.

Specification of Letters Patent. Patented Mar. 28, 1922.

Application filed August 4, 1920. Serial No. 401,162.

To all whom it may concern:

Be it known that I, SIDNEY G. BARNSTEAD, a citizen of the United States, and a resident of Cambridge, in the county of Middlesex 5 and Commonwealth of Massachusetts, have invented certain new and useful Improvements in Condensers, of which the following is a full, clear, and exact specification.

The object of this invention is the construction of an improved device for the condensation of water from a still, the same being especially designed for use in connection with a boiler heated by means of a gas burner. My improved condenser consists 10 essentially of two concentric spaced cylinders into the annular chamber of which cold water is supplied, and through the inner cylinder of which the vapor of the boiling water is passed, the inner cylinder having 15 an oblique partition attached at its upper edge to this cylinder but spaced from its lower and lateral surfaces, whereby the steam and vapor are forced into contact with the coolest portion of the inner cylinder and 20 hence the more rapidly condensed.

In the drawings forming part of this specification, Fig. 1 is a side sectional elevation of a gas burner and still with a condenser made in accordance with my invention, 25 Fig. 2 is a cross section on the line 2—2 in Fig. 1.

The steam producing portion of the still consists of a casing 1 provided with an apertured base 2 which supports a burner 3. Above the burner is a hollow ring 4 adapted to receive water through a tube 5, and having numerous vertical tubes 8 connecting it with the receptacle 6. This receptacle 6 has a mouth 7 and a flange 9 provided 30 with openings 10 for the escape of the products of combustion. Upon this mouth 7 there is fastened by means of thumb-nuts 11 a plate 12 from which rises the vapor escape pipe 13, the upper end of the latter having 35 an elbow 14 which opens into the condenser proper.

As shown in Fig. 2, the body of this condenser is composed of two sheet metal cylinders of unequal diameter, the smaller being 40 spaced within the larger to form an annular space 15. The outer cylinder 16 and the inner cylinder 17 are attached to heads 19 and 20 which taper down to a fit on the elbow 14, the head 19 tapering more than the head 20 in order to be brazed or soldered thereto 45 as well as to the elbow.

The head 21 at the other end of the cylinders is stepped to provide two seats 22, 23 for the reception of the two cylinders, and to render the annular chamber 15 water 50 tight in its separation from the chamber 24 within the cylinder 17.

A constant supply of cold water is supplied to the annular chamber through a pipe 25 leading into the lowermost part of the same, and the circulation is maintained therein by the outlet pipe 26 rising from the highest part of the chamber 24 and then descending to a point directly over the cup 27. This cup is supported by and communicates with a tube 29 whose lower portion 55 communicates with the tube 5 so that the water from the chamber 24 passes to and maintains the supply in the boiler tubes and receptacle 6. Whenever the level in this 60 receptacle rises above the holes in the small tube 30 located within the tube 29, the excess escapes through such holes 31 down through the pipe 30 to any suitable drainage.

The cock 32 is for the purpose of draining 65 out the boiler tubes and receptacle whenever desired, and also for obtaining a supply of hot water for any purpose.

Within the chamber 24 and attached to the upper wall thereof is an oblique partition 85 33 whose lower edge and side edges are spaced from the cylinder 17 as shown in Fig. 2, its obliquity being such that its lower edge is farther away from the elbow 14 than its upper end.

At the lowermost part of the head 21 is 90 an outlet pipe 34 for the delivery of the distilled water to any desired receptacle.

The operation of this still is as follows: As the water in the boiler tubes 8 and the 95 receptacle 6 is put into ebullition through the effect of the heat from the burner 3, the vapor arising therefrom passes through the pipe 13 and thence into the chamber 24. Here it meets the oblique partition 33 and is 100 diverted into direct contact with the portion of the cylinder 17 nearest the edges of the partition, and also nearest the freshest and coldest part of the inflowing water coming from the pipe 25. Consequently, the steam 105 and vapor passing down the chamber 24 is quickly condensed to water and descends through the pipe 34.

What I claim is:

A condenser comprising two concentric 110 spaced unequal slightly inclined cylinders, the space between the cylinders having

means for the circulation of a cooling fluid through it, and the inner cylinder having means for the delivery of vapor into its highest end, and also having an oblique plate attached to the upper surface of the cylinder and having its ends spaced from the lower portion of the surface of the cylinder, the lower end of the plate being farther from the vapor-entrance than its upper end. In testimony that I claim the foregoing invention, I have hereunto set my hand this 31st day of July, 1920.

SIDNEY G. BARNSTEAD.
